United States Patent Office

Des. 218,178

Patented July 28, 1970

218,178

GOLF PUTTER

Karsten Solheim, 10412 N. 37th St.,
Phoenix, Ariz. 85028

Filed Aug. 21, 1969, Ser. No. 18,992

Term of patent 14 years

Int. Cl. D21—01

U.S. Cl. D34—5

FIG. 1 is a perspective view in elevation of the front of a golf putter embodying my new design;

FIG. 2 is an end view of the heel in elevation of same;

FIG. 3 is a front view in elevation of same;

FIG. 4 is a rear view in elevation of same;

FIG. 5 is a perspective view in elevation of the rear of same;

FIG. 6 is a sectional view taken on line 6—6 of FIG. 1; and

FIG. 7 is a bottom view of same.

The shaft of my putter is shown fragmentarily in FIGS. 1 through 4 for convenience of illustration.

I claim:

The ornamental design for a golf putter, substantially as shown and described.
